SNOW SHOVEL

Ellsworth W. Severance, Stratford, Conn., assignor of one-third to Raymond E. Severance, one-third to William L. Severance, and one-third to Mrs. Paul E. Herrmann, all of Stratford, Conn.

Filed May 26, 1961, Ser. No. 65,367

Term of patent 7 years

(Cl. D39—1)

The dominant features of my new design reside in the full line portions of the drawing.

I claim:

The ornamental design for a snow shovel, as shown and described.
